UNITED STATES PATENT OFFICE.

JOSEPH H. HUNTER, OF DETROIT, MICHIGAN, ASSIGNOR TO DETROIT INSULATED WIRE COMPANY, OF DETROIT, MICHIGAN, A CORPORATION OF MICHIGAN.

NONSTRETCHABLE CORD.

Application filed March 20, 1922. Serial No. 545,395.

To all whom it may concern:

Be it known that I, JOSEPH H. HUNTER, a citizen of the United States of America, residing at Detroit, in the county of Wayne and State of Michigan, have invented certain new and useful Improvements in Non-stretchable Cords, of which the following is a specification, reference being had therein to the accompanying drawings.

10 The invention relates to the manufacture of non-stretchable cord particularly designed for use as robe rails, coat hangers and for similar purposes, and the invention consists in the construction as hereinafter set forth.

In the drawings:

Figure 1 is an enlarged sectional side elevation of a portion of the cord;

20 Figure 2 is a cross-section thereof;

Figures 3 and 4 are views similar to Fig. 2 showing modified constructions;

Figures 5 and 6 are sectional perspective views showing the manner of securing a fabric cover on the cord.

25 The characteristics of my improved cord are: First, that it is flexible; second, that it is comparatively non-stretchable; third, that it is of a diameter suitable for use as a robe rail or similar article and is capable of being provided with an ornamental covering. For imparting the non-stretchable characteristic there is employed either a link chain or other flexible non-stretchable unit, and for imparting the desired size together with 30 flexibility, there is a body of yielding resilient material. In detail and as shown in Figures 1 and 2, A is a link chain surrounding which is a body B formed of a rubber compound either solid or sponge. C is a 35 braided fabric surrounding the body B and either constituting an ornamental covering or a lining to which said covering may be 40 secured.

45 In the construction shown in Figure 3, the chain A is first surrounded by a filler of jute, cotton or other fibrous material, as indicated at D, and surrounding this is the rubber conduit B' and the braided covering C' as above described. As shown in Figure 4, in place of the link chain, a core E is 50 formed either of a solid or of a fibrous

cord of such a character as to be relatively non-stretchable. This is surrounded by a filler D' and the latter by a filler B' of the rubber compound, as previously described. 55 With all of the constructions the outer portion of the body is formed of the rubber compound, which will impart both flexibility and permanency of shape in cross-section.

60 Where it is desired to cover the cord with an ornamental material, such, for instance, as velvet, this may be secured in any suitable way. I have, however, shown in Figures 5 and 6 two different methods of 65 attaching such covering. As shown in Figure 5, a wedge-shaped gore is made in the rubber body extending longitudinally of the core. The covering material F is then wrapped about the body with its edges 70 tucked into the core, after which a wedge of rubber or similar substance is forced into the core and is vulcanized or otherwise secured therein. In Figure 6, instead of forming the gore, the rubber body is merely slit 75 and the fabric, after being wrapped about the body, has its edge portions tucked into the slit, being cemented or otherwise secured in position.

What I claim as my invention is:

1. A cord for robe rails and the like, comprising a non-stretchable core, a surrounding body, and a covering for said body wrapped thereabout and having its edge portions tucked into a slit in the body.

2. A cord for robe rails and the like, comprising a non-stretchable core, a body surrounding the same to enlarge the diameter thereof, and a cover surrounding said body having its edge portions tucked into a 90 longitudinal slit in the body and cemented.

3. A cord for robe rails and the like comprising a link chain, a surrounding body including a zone formed of a rubber compound, and a fabric covering for said body.

4. A cord comprising a link chain, a surrounding body including a zone formed of resilient material, and a covering for said body.

In testimony whereof I affix my signature.

JOSEPH H. HUNTER.
